PROCESS FOR REMOVING SOLVENT FROM
SOLVENT-TREATED MATERIAL

Michele Bonotto, Evansville, Ind., assignor, by
mesne assignments, to American Soya Prod-
ucts Corporation, Evansville, Ind., a corporation
of Indiana

Application July 15, 1935, Serial No. 31,541

6 Claims. (Cl. 202—46)

This invention relates to processes of removing solvent from materials treated with solvent and apparatus for use in connection therewith.

In the batch treatment of material such, for example, as soya beans for the purpose of extracting oil, it has been customary to place the material to be treated in an extractor and to pass solvent, such as gasoline, through the material. The solvent is finally conveyed from the extractor to a holder where it may be distilled and separated from the extracted oil.

In order to remove the solvent which remains in the soya bean or other material from which oil has been thus extracted, it has been customary to pass steam through the material for the purpose of carrying off the solvent. If the removal of the solvent is conducted at atmospheric pressure the steam is introduced into the bottom of the extractor and allowed to pass through the mass of material and the admixed steam and solvent carried thereby are conveyed from the top of the extractor to a condenser. When the removal of solvent is conducted under vacuum, the mass of material from which the solvent is to be eliminated is usually transferred to a drier where the material is agitated and vacuum applied for the purpose of eliminating the solvent at low temperature. Such apparatus requires a dust collector to be inserted between the drier and the suction device to prevent small particles from reaching the pumps or condenser through the ejectors.

The methods of removing solvent hereinabove mentioned are objectionable in that when steam is applied to the mass of material in the extractor, a drop in temperature, due to quick evaporation of the solvent, takes place and condensation occurs which makes it practically impossible to efficiently remove the solvent. The condensation of steam causes clogging which makes it very difficult for the admixed steam and solvent to open its way through the mass of material in the extractor. It thus becomes necessary to evaporate not only the solvent but also the condensed water. Superheating of the steam to a high degree does not overcome this difficulty and, furthermore, the use of highly superheated steam is undesirable if coagulation of the protein in the solvent-treated material is to be avoided. While the solvent-treated material may be transferred from the extractor to an agitator and drier device, such apparatus is expensive and the additional handling of the material increases unduly the length of the operation and the expense thereof.

By the use of my process and apparatus herein described, the need for atmospheric agitator and drier constructions and for vacuum driers with dust collectors and expensive fittings is eliminated.

The object of the present invention is to devise a process and apparatus for removing solvent from solvent-treated material by the use of steam, without removing the material from the extractor in which the oil extraction has taken place and 10 without having such condensation occur as will interfere with the efficiency of the steam for carrying off the solvent.

In the drawing I have shown one form of apparatus for use in carrying out my process, said 15 apparatus comprising an extractor in which material such as soya beans and the like may be treated with solvent for the purpose of extracting oil from the material, and in which the solvent-treated material remains until the solvent 20 remaining after extraction has been removed.

Fig. 1 is a vertical sectional view of apparatus embodying my invention.

Fig. 2 is a horizontal section, on a reduced scale, taken on the line 2—2 of Fig. 1, looking 25 downwardly as indicated by the arrows.

In that embodiment of the invention shown in the drawing, 10 indicates a cylindrical extractor housing having a conical lower portion 11 and conical upper portion 12. A strainer 13 is secured to an annular flange 14 at the top of the conical portion 12. Solvent may be introduced or withdrawn through the conduit 15 at one side of the top 16 of the extractor. A vapor nozzle 17 projects from the top 16 and may be connected with a condenser (not shown). At the bottom of the conical portion 11 is another strainer 18. A conduit 19 enters the bottom 20 of the extractor, and like the conduit 15 provides a solvent nozzle through which the solvent may be introduced into or withdrawn from the extractor.

The parts described comprise conventional extractor apparatus. To make such apparatus serve my purpose of removing solvent from solvent-treated material, I provide a steam pipe 21 which carries superheated steam through valves 22 to a plurality of steam conduits in ring form which surround the extractor 10. In the present embodiment three of the ring conduits 23 are provided. Each ring 23 is supported by brackets 23' and has a plurality of nozzles 24 extending downwardly from the ring through the extractor wall 10 into the interior of the extractor as indicated at 25. In an extractor of approximately 50 55

20 feet overall length, five feet in diameter, the nozzles 24-25 penetrate the extractor interior six to ten inches from the extractor wall 10. This arrangement permits the steam to be forced toward the center of the mass in the extractor and prevents collection or condensation of steam in the nozzles. The nozzles 24 of one ring may be staggered with respect to those of an adjacent ring.

10 The extractor is thus divided into superposed theoretical zones indicated in the drawing at A, B and C. The number of zones and rings 23 and the distances between said rings carrying nozzles 24-25 depends upon the kind and quantity of solvent to be eliminated.

15 As an example of my invention I shall describe an extractor and drier apparatus approximately twenty feet in length, five feet in diameter, used for the extraction of oil from a charge of approximately 4600 pounds of soy bean flakes by means of gasoline, under vacuum. The vapor nozzle 17 is connected with vacuum producing equipment. After the oil extraction is finished and the solvent and oil withdrawn, the conduits 15 and 19 are closed by means of any suitable valves and the condenser conduit 17 is opened. According to my experiments the soy bean flakes will not contain, at the completion of the extraction cycle, more than fifty percent gasoline solvent, or 2300 pounds.

20 I have found that approximately ninety percent of the solvent will be evaporated at a very rapid rate without assistance by the admission of steam directly to the extractor drier. Only 25 the final ten percent of solvent to be extracted requires the introduction of steam to accomplish its removal in a reasonable length of time. If the vacuum producing equipment is capable of removing the gasoline vapor at the rate of 2760 30 pounds per hour, ninety percent of the solvent will have evaporated in forty-five minutes and the initial temperature of 160° F. will have been reduced to 108° F. When a temperature of 108° F. is reached, I estimate that approximately 475 35 pounds per hour maximum steam should be admitted into the extractor.

40 The vacuum producing equipment should have capacity to handle the steam and the remaining solvent at the rate of about 920 pounds per hour 45 in order to remove the remaining solvent estimated at 230 pounds in fifteen minutes and to maintain a vacuum of 27.55 inches of mercury which corresponds to a temperature of 180° F. In other words, by the time the charge in the 50 extractor reaches a temperature of 180° F., the vacuum equipment will have established and be capable of maintaining a vacuum sufficiently high to prevent condensation of the steam at that temperature.

55 The required quantity of steam, instead of being introduced from the bottom of the extractor as in the prior art, will be introduced in successive stages by the nozzles communicating with the steam rings. Through the steam ring below the zone A, I first introduce superheated steam at the rate of approximately 70 60 pounds per hour. When the temperature in zone A is equal to the temperature of the steam at the existing condition of vacuum steam will be admitted through the steam ring under the zone B at the rate of approximately 158 pounds per hour, while the steam ring under the zone A is still blowing. After the temperature in zone A reaches the temperature of the steam under the 70 existing conditions of vacuum, steam is admitted

75 through the steam ring under zone C at a rate of approximately 237 pounds per hour, and when the temperature of the mass reaches the temperature of the steam under the existing condition of the vacuum, all of the solvent will have been evaporated and the mass will be perfectly dry. At that point the steam starting from the bottom rings is shut off and after breaking the vacuum the extractor is unloaded in any suitable manner.

80 If the evaporation of the solvent takes place at atmospheric pressure, the same general thermo-dynamic calculations must be made at atmospheric pressure and instead of connecting the vapor nozzle 17 with a vacuum producing 85 equipment, the above nozzle is connected directly with a condenser. The length of the zones must be decreased if a solvent is used with higher boiling point. If I use a solvent with a boiling range, for example from 180° to 200° F., instead of three zones, as in the case I have already described, I subdivide the extractor into four zones assuming that the same degree of superheating is to be used as in my present case. The steam will be introduced in the same way 90 as in the vacuum process.

95 The length of the zones, that means the distance between the steam rings 23, varies according to the quality of the solvent and according to the degree of superheating of the steam. The quantity of B. t. u. to be sent into each zone must be in excess of the quantity of B. t. u. theoretically necessary to evaporate the solvent in order to avoid condensation in the charge of material of the steam and to maintain the material at a temperature higher than the steam that is coming from the ring below each zone.

100 It is to be understood that the quantities of materials, temperatures and times herein mentioned are referred to by way of example and that they may be varied according to the size and capacity of the equipment, the kind of solvent, the temperature of the steam, and other conditions attending the extraction and drying operations.

105 It will also be understood that, under some conditions, I may prefer to reverse the order of treatment with steam of the material in the superposed zones as herein described; that is, I may desire to inject steam into the zones C, 110 B and A in the order stated and to carry off the admixed steam and solvent through the bottom 20 of the extractor.

I claim:

115 1. The process of extracting oil from material by means of solvent in an extractor and drying the extracted material without removal from the extractor, which comprises injecting steam into superposed zones of the solvent-treated material, said steam being first introduced in the 120 uppermost zone and the injection continued until the temperature of the material has been raised to a predetermined point, said steam being then injected into the next lower zone and injection continued in the upper zone, until 125 steam has been injected into each zone including the lowermost and the temperature of each zone raised to said predetermined point, and carrying off the admixed steam and solvent from the material, the rate of injection of the steam being progressively greater for each successive zone.

130 2. The process of removing solvent from solvent-treated material, which comprises injecting steam into superposed zones of the material,

the steam injections for the several zones commencing at successive intervals of time, the rate per pound per hour of steam injection being increased for each zone over the previously treated zone, said steam injection being continued in each of the zones until all have been steam-treated, and carrying off the admixed steam and solvent from the material.

3. The process of removing solvent from solvent-treated material, which comprises injecting steam into superposed zones of the material, the steam injections for the several zones commencing at successive intervals of time, beginning with the uppermost zone and progressing downwardly, and the rate of injection being progressively greater for each successive zone, continuing said steam injection in each of the zones until the lowermost zone has been sufficiently treated, and carrying off the admixed steam and solvent from the material.

4. The process of removing solvent from solvent-treated material, which comprises carrying off part of the solvent under vacuum, injecting steam into superposed zones of the material, the steam injections for the several zones commencing at successive intervals of time, and the rate of injection being progressively greater for each successive zone, continuing said steam injection in each of the zones until all have been steam treated, and carrying off the admixed steam and remaining solvent from the material.

5. The process of removing solvent from solvent-treated material without agitating said material, which comprises injecting steam into superposed zones of the material, the steam injections for the several zones commencing at successive times, beginning with the zone nearest the steam and solvent exit and progressing in the order of their location to the zone farthest from said exit, the steam injections continuing in each zone until all have been treated, the rate of injection being progressively greater for each successive zone, and at the end of said treatment carrying off the admixed steam and solvent from the material.

6. The process of removing solvent from solvent-treated material without agitating said material, which comprises injecting steam into superposed zones of the material, the steam injections for the several zones commencing at successive times, beginning with the zone nearest the steam and solvent exit and progressing in the order of their location to the zone farthest from said exit, the steam injections continuing in each zone until all have been treated, the rate of injection being progressively greater for each successive zone, and at the end of said treatment cutting off the steam in successive zones beginning with the last one treated, and carrying off the admixed steam and solvent from the material.

MICHELE BONOTTO.
